UNITED STATES PATENT OFFICE.

WEBSTER C. BALL, OF CLEVELAND, OHIO.

DESIGN FOR A HAND FOR TIMEPIECES.

SPECIFICATION forming part of Design No. 22,702, dated August 15, 1893.

Application filed April 26, 1893. Serial No. 471,982. Term of patent 14 years.

To all whom it may concern:

Be it known that I, WEBSTER C. BALL, a citizen of the United States, and a resident of Cleveland, county of Cuyahoga, and State of 5 Ohio, have invented and produced a new and original Design for Hands for Timepieces, &c., of which the following is a specification, reference being had to the accompanying drawing, forming part thereof, and which represents a view of a hand embodying my design.

The leading feature of my design consists in a lanceolate enlargement at the end of the hand, and a smaller, round enlargement at the base of the larger enlargement.

15 The hand A, is formed with a lanceolate en-

largement, B, at its end, and with a circular enlargement, C, of smaller diameter than the widest portion of the lanceolate enlargement, and arranged immediately at the base of such enlargement.

What I claim is—

The design for a hand for timepieces, &c., substantially as described and illustrated.

In testimony that I claim the foregoing to be my invention I have hereunto set my hand 25 this 15th day of February, A. D. 1893.
